UNITED STATES PATENT OFFICE

CHARLES ADLER, JR., OF BALTIMORE, MARYLAND, ASSIGNOR TO THE ADLER SAFETY CONTROL COMPANY, OF BALTIMORE, MARYLAND, A CORPORATION OF MARYLAND

DESIGN FOR A COMBINED HEAD AND CASING FOR TRAFFIC SIGNALS

Application filed May 19, 1931. Serial No. 39,898. Term of patent 14 years.

To all whom it may concern:

Be it known that I, CHARLES ADLER, Jr., a citizen of the United States, residing in the city of Baltimore and State of Maryland, have invented a new, original, and ornamental Design for a Combined Head and Casing for Traffic Signals, of which the following is a specification, reference being had to the accompanying drawings, forming a part thereof, showing my design, in which:

Fig. 1 is a plan view of a combined head and casing for traffic signals, showing my new design; and

Fig. 2 is a side elevation thereof.

I claim:

The ornamental design for a combined head and casing for traffic signals, as shown. In testimony whereof I affix my signature.

CHARLES ADLER, JR.
